UNITED STATES PATENT OFFICE

138,688

DESIGN FOR AN AVIATION ENGINE OIL TEMPERATURE REGULATOR HOUSING

Fred M. Young, Racine, Wis.

Application July 26, 1943, Serial No. 110,771

Term of patent 14 years

(Cl. D71—1)

To all whom it may concern:

Be it known that I, Fred M. Young, a citizen of the United States, residing at Racine, in the county of Racine and State of Wisconsin, have invented a new, original, and ornamental Design for an Aviation Engine Oil Temperature Regulator Housing, of which the following is a specification, reference being had to the accompanying drawing, forming a part thereof.

Figure 1 is top plan view of an aviation engine oil temperature regulator housing showing my new design.

Figure 2 is an end elevational view of my new

design, wherein the tubes are shown in dotted lines.

Figure 3 is a fragmentary side elevational view, showing the upper portion thereof on a somewhat reduced scale.

The characteristic features of my design are shown in full lines.

I claim:

The ornamental design for an aviation engine oil temperature regulator housing, as shown and described.

FRED M. YOUNG.
